UNITED STATES PATENT OFFICE

149,115

DESIGN FOR A HEATER

Charles Anthony Fowler, Los Angeles, Calif.

Application November 5, 1946, Serial No. 134,526

Term of patent 3½ years

(Cl. D81—19)

To all whom it may concern:

Be it known that I, Charles Anthony Fowler, a citizen of the United States, residing at Los Angeles, in the county of Los Angeles and State of California, have invented a new, original, and ornamental Design for a Heater, of which the following is a specification, reference being had to the accompanying drawings, forming part thereof.

Fig. 1 is a perspective view of a heater, showing my new design;

Fig. 2 is a top plan view; and

Fig. 3 is a side elevational view thereof.

I claim:

The ornamental design for a heater, as shown.

CHARLES ANTHONY FOWLER.
